UNDERFEED STOKER

Cortice H. Hall, Glen Rock, N. J., assignor to
 Domestic Stoker Company, New York, N. Y., a
 corporation of Delaware

Application December 11, 1930, Serial No. 501,481

19 Claims. (Cl. 110—45)

This invention relates to burners for solid fuel and more particularly to a burner of the underfeed stoker type similar to that shown in the Hall et al. Patent 1,675,548.

5 In the use of burners of the underfeed type in which the fire pot is stationary it has been found that cracks form in the bed of the burning fuel with the result that air escapes more rapidly through these cracks causing high stack losses and necessitating the supplying of a greater quantity of air to the burner to obtain complete combustion. It has also been found that where the rim of the fire pot is stationary, masses of matted clinker build up at the edges 10 of the fire pot and where the furnace is small, as in the household furnaces, these pieces of matted clinker often bridge over the space between the rim and the lining of the furnace and so prevent the proper removal of the ashes and 15 clinkers.

20 It has also been found that fine particles of fuel dust pass through the perforations in the fire pot and fall to the bottom of the casing surrounding the fire pot. These particles are 25 objectionable not only in that they soon clog up the air conduit and interfere with the proper supplying of air to the burners, but they also present a hazard in that they may be easily ignited, because of their fine state of subdivision 30 and the excess of air present, from the heat radiated from the fire pot.

35 It is an object of the present invention to provide an improvement in this type of underfeed burner and to avoid the above objectionable features. It is a further object to provide improved means for gently agitating the fuel at the surface of the fire bed and to provide means for evenly distributing the ashes as they are discharged from the fire pot and for preventing the 40 building up of masses of clinker on the rim of the fire pot. It is also an object of the invention to provide means for automatically discharging any fine particles of fuel or ash which may be deposited within the chamber surrounding 45 the fire pot. Other objects will become apparent.

50 In describing the invention reference will be made to the drawings in which Figure 1 is a plan view of a heating unit with the furnace shown in section. Figure 2 is a vertical section taken on the line 2—2 of Figure 1, with the top of the furnace structure broken away. Figure 3 is a plan view of an underfeed stoker embodying my invention, the view showing the structure broken away on line 3—3 of Figure 4 in

order to illustrate the driving mechanism. Figure 4 is a vertical section taken on the line 4—4 of Figure 3. Figure 5 is a vertical section taken on the line 5—5 of Figure 4.

The invention is described in connection with a heating unit in which solid fuel is fed from a hopper 10 outside of the furnace 11 to the burner positioned within the furnace 11 and in which air is supplied for the combustion in the burner from an air blower 12. The ashes 10 from the burner are removed from the furnace pit by a conveyor 13 in the conduit 14 and are lifted in the elevator 15 so that they will fall into an ash receiving can 16, also outside of the furnace. It will be apparent, however, that the invention may be utilized in other heating units and it is not intended to restrict it to the particular embodiment described.

The fuel to be consumed in the burner may be fed to it by means of a continuously or 20 intermittently rotating spiral conveyor 17 on a shaft 18, which is driven by any suitable driving mechanism, for example, such as described in the Hall et al. Patent 1,638,396 or the Wightman Patent 1,703,130. This conveyor is 25 enclosed within a pipe or conduit 19 which is connected at its outer end to the fuel hopper 10 and at its inner end to an elbow shaped conduit member 20 for changing the direction of the fuel and carrying it upwardly into the lower section 30 21 of the fire pot. The upper section 22 of the fire pot is suspended slightly above the lower section 21 by means of an annular frame 23 which rests upon an annular bearing ring 24 in the upper portion of the outer casing 25 of 35 the burner unit. This section of the fire pot may be removably connected to the support frame 23 by means of stove bolts 26, 26 countersunk into the upper rim of this section of the fire pot. A suitable packing ring 27 may be 40 inserted between the edge of the fire pot 22 and the frame 23. A ring 28 extending around the periphery of the frame 23, is supported from the upper surface of that frame and forms the outer rim of the burner unit.

The frame 23 fits tightly within the annular bearing ring 24 to prevent leakage of air at this point and is held in position by gravity. In order to prevent displacement of the upper portion of the burner when the fire pot is inverted during installation or transportation, the lugs 29, 29, shaped to extend over a lip on the outer surface of the frame 23, are fastened around the upper portion of the casing 25 by means of bolts 30.

45

50

55

The conveyor shaft 18 extends through a suitable bushing (not shown) at the outer surface of the elbow shaped conduit 20 and a bevelled spur gear 31 is fixed to the end of the shaft. 5 This spur gear meshes with a bevelled spur gear 32 fixed to a vertical stub shaft 33 supported in the bearing 34. A gear 35 is fixed to the upper end of the shaft 33 and meshes with a ring gear 36 which is fixed to or integral with the 10 inner surface of the frame 23 supporting the upper section of the fire pot.

The sections of the fire pot are completely enclosed within the frame 23 and the casing 25, the latter being in communication with an annular 15 air conduit 37 which surrounds the fuel conveying pipe 19. The conduit 37 is connected to the air blower 12 through the conduit 38. The upper and lower sections of the fire pot contain 20 perforations 39, 39, extending around the fire pot, which perforations permit air from the blower 12 to pass through the fuel for the combustion in the burner.

The lower portion of the casing 25 is shaped to provide an elongated cylindrical depression 25 40 in which a rotatable discharge valve is located. This valve is constructed with cylindrical end portions 41, 41, adapted to bear upon cylindrically shaped bearing surfaces in the depression 40. These end portions are connected by vanes 30 42 arranged as indicated more clearly in Figure 5. An open slot 43 in the bottom of the cylindrical depression 40 extends the length of the vanes 42, and the latter are so arranged that at least two vanes are at all times in contact throughout their lengths with the cylindrical 35 cal surface on opposite sides of the slot 43.

A lever 44 is fixed to the base of the gear 31 for rotation with the shaft 18. This lever is so positioned that at each rotation of the shaft 18 40 its lower extremity 45 contacts with the upper portion of one of the vanes 42 throughout a sufficient arc to move such vanes a distance that will insure contact between the lever 44 and a succeeding vane upon the next rotation of the shaft 18.

The valve shown is an integral unit which may be removed, if necessary for cleaning, etc. through the opening 46 in the casing 25, which opening is closed by an ordinary resilient expansion 50 plug as illustrated at 47.

The heating unit described above may be used to advantage in a furnace having a corrugated inner surface as illustrated at 49 in Figures 1 and 2 or in one having a rectangular lining or a 55 cylindrical lining, as illustrated by the dotted line 48 in Figure 3.

In operating my improved underfeed stoker, which is particularly adapted for use in small domestic furnaces such as are commonly used 60 in heating homes, the shaft 18 is rotated to force the fuel up through the fire pot at such a rate that the fuel is completely burned before being discharged from the rim 28 of the fire pot, the required air being supplied through the perforations 39, 39. This rotation of the shaft 18 rotates the frame 23 upon the bearing 24 together with the upper section of the fire pot which is suspended from the frame. By this rotation of the upper section of the fire pot the fuel in the fire bed is moderately agitated to insure complete 70 combustion and to avoid the formation of cracks in the body of the fire bed.

This rotation also inhibits the formation of large masses of clinker in the fire bed and if such masses are formed so as to extend beyond

the rim of the fire pot sufficiently to strike the walls of the furnace, as illustrated by the dotted line 50 in Figure 1, they will be scraped off by striking the corrugated, angular or smooth wall of the furnace. The clinkers knocked off in this 5 manner and the ashes discharged from the fire pot will be evenly distributed and will fall onto the directing plates 51 which will guide them to the opening 52 at the inner end of the ash remover conduit 14 where they will be conveyed 10 by the screw conveyor 13 to the bottom of the elevator 15 and through that to the ash receiving can 16, for example, as described in the Hall Patent 1,756,025.

During the combustion of the fuel some fine 15 particles of fuel and ash may fall through the perforations 39, 39 into the casing 25 surrounding the lower portion of the burner. These small particles will collect in the segments between the vanes 42 of the valve positioned in 20 the depression 40, and by the intermittent rotation of this valve through the lever 44, these fine particles will be automatically discharged through the slot 43. With the arrangement of vanes illustrated in the drawings, vanes extending 25 on opposite sides of the slot 43 will at all times be in contact with the edges of the depression 40 so that the air blown into the casing 25 may not escape through the slot 43.

Although I have described the invention in 30 connection with a unit in which the upper section of the fire pot and the rotating valve are driven by the fuel feeding shaft, these parts may also be driven by some other means, such, for example, as by a suitable driving connection 35 from the ash removing shaft. In referring to a particular construction and arrangement of parts in describing the invention, it is not intended to limit the invention to the particular features illustrated, it being apparent that it 40 may be applied in many modified forms by one skilled in the art. The terms used in describing and claiming the invention have been used in an illustrative sense and not as terms of limitations, and it is intended that all equivalents of 45 these terms be included within the scope of the appended claims.

What I claim is:

1. A burner unit of the underfeed type, comprising a perforated fire pot and a spiral conveyor adapted to supply fuel to the lower portion of the fire pot, a casing surrounding said fire pot and communicating with a source of air supply, an aperture in the lower portion of said casing, a valve for discharging solid 50 particles positioned to close said aperture and having radial vanes contacting with the casing on opposite sides of the aperture whereby the valve always maintains the aperture sealed to prevent the discharge of air therethrough, and a lever fixed for rotation with the shaft of the spiral conveyor and adapted to intermittently rotate said valve with each rotation of the shaft.

2. A burner of the underfeed type, comprising a perforated fire pot and a spiral conveyor for 65 supplying fuel to the lower portion of the fire pot, a casing surrounding said fire pot and communicating with a source of air supply, said casing having a cylindrically shaped depression and an elongated slot in said depression, a valve for discharging solid particles, said valve having cylindrical ends adapted to bear upon the surface of the depression and having radial vanes 70 so positioned that at all times during the rotation of the valve the outer ends of vanes will 75

contact with the cylindrical surface of the depression on opposite sides of the slot, thereby sealing the slot to prevent discharge of air there-through, and a lever fixed for rotation with the 5 shaft of the spiral conveyor and adapted to contact with a vane of the valve to rotate the same a sufficient distance to assure contact with a succeeding vane upon further rotation of the shaft.

10. 3. A burner unit comprising an underfeed fire pot having a fixed lower section extending substantially to the combustion zone through which the fuel passes upwardly to the combustion zone without substantial agitation and an upper section having air inlet apertures extending substantially to its lower edge, said section being adapted to rotate to give a gentle agitation to the upper surface of the fire bed, means for supplying fuel to the fire pot, and means 20 actuated by said fuel supply means for rotating said upper section.

4. In the burning of fuel in an underfeed burner, the steps comprising passing the fuel upwardly through the lower main portion of the fuel bed to the combustion zone without substantial movement of the fuel particles relative to each other and regularly rotating the upper portion of the fuel bed in accordance with the feed of fuel to the burner.

5. In the burning of fuel in an underfeed burner, the steps comprising passing the fuel upwardly through the lower main portion of the fuel bed to the combustion zone without substantial movement of the fuel particles relative to each other and giving the upper portion of the fuel bed a regular gentle rotary motion relative to the lower portion throughout the period of operation of the burner.

6. A burner unit of the underfeed type comprising a fire pot, a conveyor adapted to supply fuel to the lower portion of the fire pot, said fire pot comprising a perforated lower fixed section and a rotatable upper section having perforations extending substantially to its lower edge, and means for supplying air to the fuel in the lower and upper sections.

7. A method for burning fuel in an underfeed burner, comprising progressing the fuel upwardly through the lower main portion of the fuel bed to the combustion zone with the minimum of movement of the fuel particles relative to each other, continuing the movement of the fuel particles upwardly through the combustion zone while gently agitating them in accordance with the progressive supplying of fuel to the fuel bed.

8. A burner unit of the underfeed type, comprising a fire pot, a conveyor adapted to supply fuel to the lower portion of the fire pot, said fire pot having a lower fixed section extending substantially to the combustion zone and a rotatable upper section having air inlets extending substantially to its lower edge, said upper section providing a rotatable outer rim for the unit over the outside edge of which the solid particles of combustion are discharged, and means for rotating the said upper section.

9. A burner unit of the underfeed type, comprising a fire pot, a conveyor adapted to supply fuel to a fixed lower section of the fire pot, which lower section extends substantially to the combustion zone, a rotatable upper section of the fire pot having air inlet apertures extending substantially to its lower edge, said upper section providing a rotatable outer rim for the unit,

and means for rotating the said upper section at a definite rate dependent upon the rate of feed of fuel by the conveyor.

10. A burner unit of the underfeed type, comprising a fire pot having a fixed lower section extending substantially to the combustion zone and adapted to receive fuel from a conveyor and direct it upwardly to the combustion zone without substantial agitation, said fire pot also having an upper section containing air inlet 10 perforations substantially to its lower edge and providing a rotatably mounted outer rim over which the solid particles of combustion are discharged, and means for rotating said rim in accordance with the rate of feed of fuel to the 15 fire pot.

11. A burner unit of the underfeed type, comprising a fire pot, a conveyor adapted to supply fuel to the lower portion of the fire pot, said fire pot consisting of a lower fixed section extending upwardly from the end of the fuel conveyor and a rotatable upper section containing air apertures substantially to its lower edge, means for rotating said upper section in accordance with the feed of fuel to the burner, and 20 means for supplying air to said upper section.

12. A burner unit of the underfeed type, comprising a fire pot, a conveyor adapted to supply fuel to the lower portion of the fire pot, said fire pot consisting of a lower fixed section extending upwardly from the end of the fuel conveyor and having air inlet apertures and a rotatable upper section containing air apertures extending substantially to its lower edge, means for rotating said upper section in accordance 30 with the feed of fuel to the burner and means for supplying air to said upper and lower sections.

13. A burner unit as defined in claim 11 in which the fuel conveyor is operated intermittently.

14. A method for burning fuel in an underfeed burner, comprising progressing a core of fuel upwardly into the combustion zone with the minimum of movement of the fuel particles 45 relative to each other, continuing the movement of the core of fuel particles upwardly through the combustion zone, while subjecting the outer portion of the core to rotary motion to gently agitate the outer layer thereof in the combustion 50 zone.

15. A burner unit of the underfeed type, comprising a perforated fire pot, a conveyor adapted to supply fuel to the lower portion of the fire pot, a casing surrounding the fire pot and connected to a source of supply of air under pressure above atmospheric pressure, means to discharge fine particles of ash or fuel deposited in the casing, without releasing the pressure within said casing, and means for actuating said discharge means in accordance with the rate of fuel supply.

16. A burner unit of the underfeed type, comprising a perforated fire pot, a spiral conveyor adapted to supply fuel to the lower portion of the fire pot, a casing surrounding the fire pot and connected to a source of air under pressure above atmospheric pressure, a rotatable valve positioned in the casing for discharging fine particles of ash or fuel deposited in the casing, without reducing the pressure within the casing, and means actuated by the fuel conveyor for rotating said valve.

17. A burner unit of the underfeed type, comprising a perforated fire pot, a conveyor adapted 75

- to supply fuel to the lower portion of the fire pot, a rotatable upper section of the fire pot and means for rotating said upper section, a casting surrounding the fire pot and connected to a source of supply of air under pressure above atmospheric pressure, means to discharge fine particles of ash or fuel deposited in the casing, without releasing the pressure within said casing, and means for actuating said discharge means in accordance with the rate of fuel supply.
18. A burner unit of the underfeed type, comprising a perforated fire pot and a conveyor adapted to supply fuel to the lower portion of the fire pot, a casing surrounding said fire pot and communicating with a source of air supply under pressure above atmospheric pressure, an aperture in the lower portion of said casing, a rotatable valve for discharging solid particles, positioned to close said aperture and having vanes contacting with the casing on opposite sides of the aperture for maintaining the aperture sealed at all times by the valve and pre-

venting discharge of air therethrough, and means for rotating said valve in accordance with the rate of fuel supply.

19. A burner of the underfeed type, comprising a perforated fire pot, a conveyor for supplying fuel to the lower portion of the fire pot, a casing surrounding said fire pot and communicating with an air blower, said casing having a cylindrically shaped depression and an elongated slot in said depression, a valve for discharging solid particles, said valve having cylindrical ends adapted to bear upon the surface of the depression and having radial vanes so positioned that at all times during the rotation of the valve the outer ends of the vanes will contact with the surfaces of the depression on opposite sides of the slot, for sealing the slot to prevent discharge of air therethrough, and means for rotating said valve in accordance with the rate of fuel supply.

CORTICE H. HALL.
